UNITED STATES PATENT OFFICE

ALEXANDER MEISSNER, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY

METHOD FOR ELIMINATING DISTURBANCES IN RECEIVING WIRELESS TELEGRAPHY AND TELEPHONY

Application filed February 19, 1924, Serial No. 693,783, and in Germany February 24, 1923.

The invention relates to an arrangement which, by modulating a radio frequency oscillation by means of low or medium frequency at a very good efficiency, can generate a frequency slightly different from the original frequency and so improve the wireless receiving by eliminating disturbances caused by other wireless stations or atmospherics. This aim is reached by modulating the receiving frequency in such a way that the disturbing frequencies are weakened or fully annulled so that they do not act upon the receiving apparatus.

The invention will best be understood from the following detailed description when read in connection with the drawings in which:

Fig. 1 represents diagrammatically one embodiment of my invention; and

Fig. 2 illustrates diagrammatically another modification thereof.

The principle of the invention is that the incoming radio frequency and the disturbing frequency are modulated so that an altered radio frequency is led to the receiving system.

Figure 1 shows an example of such a connection in which two vacuum valves V_1 and V_2 , connected according to the balancing method, are used. The incoming radio frequency, for instance, that of the aerial A or of any other receiving system, which may be 20,000 cycles, acts upon coil L_1 . As the schematic diagram shows, this frequency acts upon the grids of the two valves V_1 and V_2 connected according to the balancing method, in the same sense. Besides, a small auxiliary generator of a frequency of 3,000 cycles for instance, acts in the opposite sense across coil L_2 upon the grids of V_1 and V_2 by working on the not straight parts of the characteristics of the two valves V_1 and V_2 . It can be attained by a proper adjustment of the working points of the valves that only one of the two modulated frequencies, either 17,000 or 23,000 cycles, is strongly developed in the tuned oscillatory circuit I, which is coupled to the plate-filament circuit. This frequency can be led to the receiver E, either directly or in the way known by means of a heterodyning circuit U which is for instance tuned to the re-

ceiving frequency of 20,000 cycles, so that the note 3,000 is audible in the telephone T.

Figure 2 shows another example of the invention. Coil L_2 is not supplied by an auxiliary generator, but the receiving currents which are already transformed into audio frequency of, for instance, 1,000 to 3,000 cycles by means of the heterodyne method, are led to coil L_2 . On the other hand, an auxiliary radio frequency oscillation, which, for instance, can be generated by a small heterodyning circuit, (auxiliary cathode valve generator) acts upon coil L_1 . Exactly as in the connection of Figure 1 a strongly developed oscillation of the frequency 17,000 or 23,000 cycles which can be transferred to the receiving circuit E, is produced in the oscillatory circuit I, when the auxiliary generator has a frequency of 20,000 cycles.

When any other frequency or an atmospheric acts upon L_1 , it is not efficient in circuit I as this circuit is only syntonized to a certain frequency.

Having thus described my invention what I desire to protect by Letters Patent is as follows:

1. In combination an input circuit tuned to a receiving frequency, a push pull amplifier having an input and an output circuit, said input circuit being coupled to said first named input circuit, a local audio frequency generator circuit coupled to said push pull amplifier input, said arrangement being adapted to combine said receiving frequency and said locally generated frequency, a tuned circuit coupled to said output circuit and heterodyne detection means coupled to said last named tuned circuit and using a beating oscillation of the same frequency as the received frequency and adapted to produce a beat note equal to said locally generated frequency.

2. A method of receiving signals which consists in combining the incoming high frequency waves with locally generated audio frequency oscillations, selectively amplifying one of the resultant composite waves, combining the amplified composite wave with a wave equal in frequency to said incoming

high frequency waves and detecting the resultant wave.

3. In combination a pair of space discharge devices arranged to substantially form a push-pull circuit having an input circuit and an output circuit, means in said input circuit for simultaneously impressing oscillations of a desired frequency in like sense on the input elements of both said space discharge devices, means in said input for impressing oscillations of another desired frequency in unlike sense on the input elements of both said space discharge devices, said first named circuit acting to combine said two frequencies and produce resultant beat frequencies in said output, means for filtering out one of the beat frequencies, means for combining the filtered beat frequency with another frequency equal to the frequency of one of said first two mentioned frequencies and means for detecting the resultant energy.

4. In a receiving system, a pair of space discharge devices arranged so as to form substantially a push-pull circuit having input and output circuits, means for collecting transmitted signal energy and impressing the collected energy in the input of said push-pull arrangement so as to affect both said space discharge devices in like sense, a local oscillator coupled to said input for impressing oscillations of a desired frequency in each of said two space discharge devices in unlike sense, said two space discharge devices acting to combine the incoming frequency with the locally generated frequency so as to produce beat notes in the output circuit of said push-pull arrangement, a circuit tuned to one of the beat note frequencies produced coupled to said output circuit and a detecting circuit coupled to said last named circuit and means for impressing on said tuned circuit energy of a frequency equal to the incoming frequency.

ALEXANDER MEISSNER.
